US00D967050S

(12) **United States Design Patent** (10) Patent No.: **US D967,050 S**
(45) Date of Patent: **** Oct. 18, 2022**

(54) **TELECOMMUNICATIONS ENCLOSURE**

(71) Applicant: **CommScope Technologies LLC**,
Hickory, NC (US)

(72) Inventors: **Roel Modest Willy Bryon**, Aarschot (BE); **Eddy Luc Cams**, Bilzen (BE); **Pieter Doultrimont**, Kermt-Hasselt (BE); **Philippe Coenegracht**, Hasselt (BE); **Johan Geens**, Bunsbeek (BE)

(73) Assignee: **CommScope Technologies LLC**,
Hickory, NC (US)

(**) Term: **15 Years**

(21) Appl. No.: **29/778,233**

(22) Filed: **Apr. 12, 2021**

Related U.S. Application Data

(62) Division of application No. 29/667,298, filed on Oct. 19, 2018, now Pat. No. Des. 916,044.

(57) **CLAIM**

The ornamental design for a telecommunications enclosure, as shown and described.

DESCRIPTION

FIG. 1 is top isometric view of a telecommunications enclosure;

FIG. 2 is a bottom isometric view thereof;

FIG. 3 is another top isometric view thereof;

FIG. 4 is another bottom isometric view thereof;

FIG. 5 a front side view thereof;

FIG. 6 is a rear side view thereof;

FIG. 7 is a left side view thereof;

FIG. 8 is a right side view thereof;

FIG. 9 is a top view thereof; and,

FIG. 10 is a bottom view thereof.

The broken lines shown in the drawings depict portions of the telecommunications enclosure that form no part of the claimed design.
